DESIGN FOR A DISPLAY RACK

William R. Wright, West Warren, Mass., assignor to Wm. E. Wright & Sons Co., West Warren, Mass., a corporation of New Jersey

Application December 11, 1937, Serial No. 73,545

Term of patent 3½ years

To all whom it may concern:

Be it known that I, William R. Wright, a citizen of the United States, residing at West Warren, in the county of Worcester and State of Massachusetts, have invented a new, original, and ornamental Design for a Display Rack, of which the following is a specification, reference being had to the accompanying drawing, forming part thereof.

Fig. 1 is a front view, and
Fig. 2 is a side view of a display rack showing my new design.

I claim:

The ornamental design for a display rack, as shown.

WILLIAM R. WRIGHT.
